SWITCH

Edwin L. Horning, Dayton, Ohio, assignor to General Motors Corporation, Detroit, Mich., a corporation of Delaware

Application September 25, 1941, Serial No. 412,327

2 Claims. (Cl. 200—5)

The invention relates to improvements in electric switches and particularly electric switches of the snap action type.

It is among the objects of the present invention to provide a snap action switch having a pliable insulating cover which not only completely seals the entire switch against moisture but is adapted to be distorted to actuate the switch thereby entirely eliminating the possibility of the operator coming into contact with any of its electrically charged parts.

A further object of the present invention is to provide a sealed snap action switch of simple structure and design, comprising a minimum number of parts and requiring a minimum time to assemble.

Further objects and advantages of the present invention will be apparent from the following description, reference being had to the accompanying drawing wherein a preferred embodiment of one form of the present invention is clearly shown.

In the drawing:

Fig. 1 is a plan view of the switch with its casing or cover shown in section, the view being taken along the line 1—1 of Fig. 2;

Fig. 2 is a side view of the switch, the cover or casing thereof being shown in section. In this view the switch is shown in a position in which one of its circuits is completed.

Fig. 3 is a view similar to Fig. 2, the casing or cover, however, being deformed to actuate the switch to close a second circuit thereof;

Fig. 4 is a view similar to Figs. 2 and 3. However, in this view the casing or cover is shown deformed to actuate the switch so that all of its circuits are open.

Referring to the drawing, the numeral 20 designates the disc-shaped base of the switch, made of any suitable insulating material. This base supports three terminals 21, 22 and 23. The terminals 21 and 23 provide stationary contacts 24 and 25 respectively while the terminal 22, interposed between terminals 21 and 23, provides means for securing the bracket 26 upon the insulating base 20. This bracket as shown in Figs. 2, 3 and 4 is U-shaped having two upstanding spaced arms 27 and 28. Each arm has a tongue-like extension, the one of arm 27 being designated by the numeral 27a and the tongue-like extension of arm 28 being designated by the numeral 28a.

The movable element of the switch which is adapted to move with a snap action is in the form of a flexible metallic strip 30 carried by the

bracket 26. This metallic strip is attached to and carried by the bracket in the following manner: Elongated slots 31 and 32 are provided in the strips 30, the distance between the inner, adjacent end of said slots being slightly greater than the distance between inner, adjacent surfaces of the upwardly extending tongue portions 27a and 28a of the bracket 26. These differences in dimensions just mentioned are provided so that when the strip 30 is placed upon the bracket, the tongue 27a of the bracket being received by the slot 31 of the strip and the tongue 28a of the bracket being received by the slot 32 of the strip, the confined intermediate portion of the strip 30 between said tongues will be biased so as to be adapted to be bowed in one direction or the other. When biased upwardly away from the bottom of the bracket 26, as shown in Fig. 1, the confined, intermediate portion of the strip 30 will urge the end portions of the strip in the opposite direction or toward the bottom of the bracket 26. In the position as shown in Fig. 2, the shape of the strip 30 is such that the contact 40, carried at one end of the strip, will engage with its cooperating stationary contact 25. However, the contact 41 attached to the opposite end of the strip 30 will lie in alignment with but spaced from its cooperating contact 24. In order to cause engagement of contact 41 with its cooperating contact 24 the operator must press and maintain pressed this end of the strip 30. The release of such pressure will immediately permit this end of the strip to flex and move contact 41 out of engagement with contact 24. However, contact 40 will maintain engagement with its cooperating contact 25 as long as strip 30 is bowed in the direction shown in Fig. 2.

When it is desired to separate contact 40 from its cooperating contact 25, the confined or intermediate portion of the strip 30 between the bracket tongues 27a and 28a must be reversed in curvature from that shown in Figs. 1 and 2. This is done by exerting pressure upon this confined portion of the strip 30 urging it downwardly or toward the bottom of the bracket 26. When this confined portion of the strip assumes the position as shown in Fig. 4, or more specifically, when it is flexed downwardly toward the bottom of the bracket 26 the ends of the strip will be quickly shifted in the opposite direction or away from the stationary contacts 24 and 25 so that contact 40 will thus be moved out of engagement with its cooperating contact 25 and therefore all circuits of the switch are broken.

A flexible pigtail connection 45 has its one end

connected to the strip 30 adjacent the contact 40 thereon while the opposite end of said pigtail connection is electrically secured to the bracket 26 by the terminal screw 22.

It has been previously stated that one of the objects of the present invention is to provide a snap action switch completely sealed against moisture and adapted to be actuated without possibility of the operator coming into contact with any of its electrically charged parts.

This object is attained by providing the switch with a pliable or flexible insulating cover designated by the numeral 70. The cover is cup-shaped and has an internal annular groove 71 adapted to receive and tightly fit about the peripheral edge of the supporting disc 20 of the switch as shown in Figs. 2, 3 and 4. The tight fit of the groove 71 of the cover about the outer peripheral edge of the disc seals the interior of the switch with its operating mechanism against moisture.

The present drawing shows the switch in a form preferably adapted for use on a washing machine for controlling the motor thereof. The numeral 72 indicates in fragmentary form the casing of the washing machine. In this casing there is provided an aperture, the inner annular edge of which is indicated by the numeral 73. The annular edge portion of the casing defining this aperture 73 is received by an outer annular groove provided in the casing or cover of the switch so that the switch assembly is securely held in this aperture 73 of the washing machine casing 72.

As has been mentioned the switch casing or cover is made up of pliable insulating material such as rubber or the like. In the outer surface of the cover are provided two disc-shaped areas 75 and 76, the latter substantially co-axial of the cover. Each disc-like portion 75 and 76 of the cover has inwardly extending lugs designated by the numerals 77 and 78 respectively. The disc-like portion 75 with its lug 77 lies over and in alignment with the end of the flexible metal strip 30 carrying the contact 41. Disc-like portion 76 of the cover and its inwardly extending lug-portion 78 lies over and in alignment with the confined portion of the strip 30 between the upwardly extending arms 27 and 28 of the bracket 26. When pressure is exerted upon the disc-like portion 75 to distort this part of the pliable switch cover or casing as shown in Fig. 3, the end of the metal strip 30 carrying contact 41 will be urged toward the stationary contact 24 so that the contact 41 on strip 30 will engage said stationary contact. As has been said before, movement of this end of the strip 30 will cause flexing of the confined portion of said strip between the upstanding arm of bracket 26 in the opposite direction or away from the bottom portion of the bracket 26 resulting in a sudden flexure of the end of the strip 30 carrying contact 40 toward the stationary contact 25 so that said contact 40 will engage with said stationary contact 25 as shown in Fig. 3. As long as the operator exerts pressure on

the disc-like area 75 of the switch casing or cover to distort it, as shown in Fig. 3, engagement of switch contacts 25 and 40, will be maintained. However, as soon as such pressure is released by the operator, contacts 41 and 24 will be separated.

From the drawings and from the foregoing description it may clearly be seen that applicant has provided an electric switch completely sealed against moisture. A switch provided with a pliable insulating cover of blister-like construction which may be distorted to operate the switch to close and open its circuits without any danger of the operator coming into contact with any of its electrically charged parts. This is particularly advantageous where the switch is used in connection with a washing machine for controlling the operation of the motor thereof for usually the floor about the washing machine 20 is wet which is conducive to dangerous shock to the operator if in any way he might come into contact with a charged part of a control switch.

Applicant has provided a sturdy switch absolutely safe against electrical shock and of simple structure and design, comprising a minimum number of parts in its make-up and consequently requiring a minimum amount of time for its assembly.

While the embodiment of the present invention as herein disclosed, constitutes a preferred form, it is to be understood that other forms might be adopted, all coming within the scope of the claims which follow.

What is claimed is as follows:

35. 1. A snap action switch comprising in combination, an insulating base; three aligned terminals on said base; a bracket secured to the base by the central terminal; a flexible strip secured to the bracket so as to compress and bias an area of said strip intermediate its ends; a contact on each end of the strip, only one contact engaging its terminal when the biased portion of the strip is bowed in one direction, the other contact on the strip engaging its terminal only while pressure is exerted upon that end of the strip, both contacts being spaced from their respective terminals when the biased portion of the strip is bowed in the other or opposite direction; and a flexible, electrical connection between the center terminal and the strip.

2. A snap action switch comprising in combination, an insulating base, three aligned terminals on said base; a U-shaped bracket secured to said base by the one, center terminal; a flexible strip anchored to the two upstanding arms of the U-shaped bracket so as to bias the portion of the strip between said two upstanding arms; a contact on each end of the flexible strip adapted to engage the respective second and third or outer terminals, the one, while the biased portion of the switch is bowed away from the center terminal, the other contact only while pressure is exerted upon that end of the flexible strip; and a flexible connection between the said center terminal and the strip.
